Primary Examiner — S. Bryan Reinholdt, Jr.*Assistant Examiner* — James T Tyree*(74) Attorney, Agent, or Firm* — Sandy Lipkin(57) **CLAIM**

The ornamental design for a toy gun, as shown and described.

DESCRIPTION

FIG. 1 is a front view of a toy gun, showing my new design; FIG. 2 is a top plan view thereof; FIG. 3 is a bottom plan view thereof; FIG. 4 is a rear plan view thereof; FIG. 5 is a left plan view thereof; FIG. 6 is a right plan view thereof; and, FIG. 7 is a perspective view thereof.

The broken lines in the drawings depict portions of the toy gun that form no part of the claimed design.
